UNITED STATES PATENT OFFICE.

WILLIAM E. JOHNSON, OF ROCK ISLAND, ILLINOIS, ASSIGNOR TO ROCK ISLAND PLOW COMPANY, OF ROCK ISLAND, ILLINOIS, A CORPORATION OF ILLINOIS.

WHEELED PLOW.

No. 905,079.

Specification of Letters Patent. Patented Nov. 24, 1908.

Application filed March 18, 1907. Serial No. 362,822.

To all whom it may concern:

Be it known that I, WILLIAM E. JOHNSON, a citizen of the United States of America, and resident of Rock Island, Illinois, have 5 invented a certain new and useful Improvement in Wheeled Plows, of which the following is a specification.

My invention relates to wheeled plows in general, but more particularly to wheeled 10 plows in which the plow beam is hung from the frame by bails or swinging connections, and especially to plows of this character in which an arrangement of foot levers is employed for lifting and lowering the plow in 15 the frame.

Generally stated, the object of my invention is the provision of an improved arrangement of foot levers and springs for lifting and lowering the plow.

20 A special object of my invention is the provision of an arrangement by which the straightening of one toggle tends to lock the plow out of the ground, while the straightening of another toggle tends to lock the 25 plow in the ground.

A further object of my invention is the provision of a device to assist the straightening out of the lifting toggle and also aid in locking the plow more securely in the ground.

30 A further object is an improved method of attaching the lifting spring to the bail.

It is also an object, of course, to provide certain details and features of improvement and combinations tending to increase the 35 general efficiency and serviceability of a wheeled plow or other implement of this particular character.

To the foregoing and other useful ends, my invention consists in matters hereinafter 40 set forth and claimed.

In the accompanying drawings, Figure 1 is a side elevation of a plow embodying my improvements. Fig. 2 is an enlarged detail of a portion of Fig. 1 illustrating the foot 45 lever arrangement embodying the principles of my invention, showing the same in position to lock the plow beam in a raised or elevated position. Fig. 3 is a similar view showing the parts in position to lock the 50 plow beam in its lowered position. Fig. 4 is an enlarged plan view of a part of Fig. 1. Fig. 5 is a detail sectional view of one of the 55 toggle joints. Fig. 6 is an enlarged detail view of the construction by which the lifting foot lever is connected with one of the toggle

arms or links. Fig. 7 is a section on line 7—7 in Fig. 6. Fig. 8 is a detail perspective view of the end of the hub on one of the toggle arms or links, which engages the hub portion of the foot levers. Fig. 9 is an enlarged elevation of a portion of Fig. 1 showing the method of attaching the lifting spring. Fig. 10 is a plan view of Fig. 9. Fig. 11 is an enlarged sectional view showing the method of shifting the position of 65 the supporting hook. Fig. 12 is a detail of Fig. 9, showing the hook in horizontal position.

As thus illustrated the frame A of the 70 plow may be of any suitable, known or approved construction, and may be supported on wheels in the usual manner. The plow beam B can be hung on bails in the usual manner, such, for example, as the rear bail O. With this arrangement the plow beam 75 with its plow b or other implement is free to be swung up and down. The usual spring D is provided for assisting in raising the plow from the ground.

The lifting arrangement consists of a bifurcated toggle arm E hung on the frame A, and another toggle arm e pivotally connected with the plow beam, the two toggle arms being pivotally joined together by a bolt e¹, and by the hub e² which is integral 80 with the arm e. This hub lockingly engages the hub portion of the lifting foot lever e³, and the arm E is loosely mounted upon the hub portion e², as shown more clearly in Fig. 6. The arm E is provided with an ear e⁴ having a set screw e⁵ adapted to bear upon the toggle arm e. With this arrangement the toggle connection thus provided 85 can be adjusted so as to permit its joint to pass to the center. In this position the toggle connection locks the plow in the ground. By depressing the foot lever e³ the plow beam will be raised to the position shown in Fig. 2, the toggle arms E and e breaking joint downwardly and rearwardly to bring 90 the plow into its raised position. In this way the foot lever e³ is applied directly to the joint or knuckle of the toggle connection by which the plow beam is lifted to raise the plow or other implement out of the 95 ground.

The arrangement by which the plow is lowered to the ground consists of a depressing foot lever F which is pivotally mounted 100 upon the plow beam at f, and which is rigid 110

with the link or toggle arm f^1 ; and another link or toggle arm f^2 which has its lower end pivotally connected with the link or arm e , by a bolt f^3 ; and the upper end of this link or 5 toggle arm f^2 is pivotally connected by a bolt f^4 with the arm f^1 , the latter being provided with a stop f^5 which tends to prevent the toggle thus formed from breaking joint in a forward direction, this stop engaging the 10 arm f^2 , as shown more clearly in Fig. 5. This housing is sufficiently high to enable the toggle to break slightly forward beyond its dead center so that it will lock and maintain the plow in its raised position. 15 When the plow is out of the ground the toggle connection consisting of the arms f^1 , f^2 are in a straightened condition, as shown in Fig. 2, and the toggle consisting of the arms E , e is in a break joint condition, as previously 20 explained.

When the plow is in the ground the toggle connection consisting of the arms f^1 , f^2 is in a break joint condition, while the other toggle connection consisting of the arms E , e 25 is in a straightened condition, as shown in Fig. 3. In this way, the toggle operated by the foot lever F is adapted to lock the plow out of the ground, while the toggle operated by the foot lever e^3 is adapted to lock the 30 plow in the ground. With this arrangement a powerful and effective lifting leverage is obtained, the lifting foot lever e^3 being always conveniently situated relative to the operator. At the same time the plow is 35 yieldingly held in both its raised and lowered positions. A slight forward push on the foot lever F is sufficient to cause the toggle arms f^1 , f^2 to break joint in a rearward direction, thus allowing the toggle arms E , e 40 to straighten out, as shown in Fig. 3. In this way a simple and effective arrangement is provided for raising and lowering the plow. To assist in straightening out the lifting toggle, I provide a spring G attached 45 in the following manner. A hanger H , sleeves on the landside axle I immediately back of the bracket which supports this axle. This arm is provided at its upper end with a hook h and at its lower end with a 50 boss or arm h^1 . This boss is provided with a slotted hole h^2 within which a bolt h^3 passes and engages a lug h^4 of the landside axle I . A lug e^6 is cast on the barrel portion 55 of the toggle arm E . One end of the spring G is secured to the hook h , the spring passes back of the landside axle inside of the frame bar A and hooks into the lug e^6 . By screwing up the nut h^7 on the bolt h^3 tension is given to the spring G . By properly 60 regulating the spring the toggle arm is more readily straightened and the plow locked more securely in the ground.

Figs. 9 and 12 show the method of attaching the lifting spring. Fig. 9 shows the 65 position of the parts when the plow is raised

to the highest position, and Fig. 12 when the plow is lowered to working position. It will be noted that the spring M is attached to the rear of the frame by an adjustable or threaded hook m , to the rear post N and attached to the rear bail O about midway of its shaft or horizontal portion by a hook P having two arms p^1 , between which the bail O passes, and which are clamped firmly to the bail by means of the clamping bolt p^2 . 70 In Fig. 9 this hook or arm P hangs downwardly from the bail in nearly a perpendicular position. As the plow is lowered and the bail swings forward, there is a slight rotation of the shaft or horizontal part of the bail turning the lower or hooked end of the arm P back toward the post N or the other point of connection of the spring. If this spring were attached directly to the bail at the same point where the arms are clamped, 80 the spring would be under its maximum tension and pulling at its greatest strength when the plows are down, as in Fig. 12, and when the plows are raised, as in Fig. 9, it would be practically without life or rendering no assistance to the lifting of the plow as the plows neared its highest position. By the use of the hooked end, however, hanging from the bail, as the bail is turned the arm has a receding motion and approaches nearer 90 the post N . By the use of this arm P considerable life is kept in the spring at all times. 95

Unnecessary tension is cut out of the spring when the plow is in its lowest position 100 by the hook or arm P having approached the post N , while considerable tension is left in the spring when the plow is in its highest position on account of the end of the hook or arm P having receded from the post N . 105 By this means an almost constant or equal tension of the spring is maintained in both positions. This is an important feature, as the greatest strength or up-pull of the spring is removed when the plows are down and 110 yet the spring has considerable tension or assisting power just at the time it is needed the most, which is at the time the plows are being locked in their raised position.

What I claim as my invention is:

1. In a wheeled plow, the combination of a pair of toggle arms, a lifting foot lever rigid with one of said toggle arms and applied to the toggle joint between the same, another pair of toggle arms, one arm of the 120 second pair being connected with an arm of the first pair, and a depressing foot lever rigid with one of the toggle arms of the second pair, each pair of toggle arms adapted to break joint when the other pair is straightened out.

2. In a wheeled plow, the combination of a toggle connection for raising the plow, a lifting foot lever mounted upon and applied directly to the toggle joint of said connec- 130

tion, and a depressing foot lever having a toggle connection with the said lifting foot lever.

3. In a wheeled plow, the combination of 5 a toggle connection and spring mechanism for raising the plow, a lifting foot lever mounted upon and applied directly to the toggle joint of said connection, and a depressing foot lever having a toggle connection with the said lifting foot lever.

4. In a wheeled plow, the combination of 10 a toggle connection and spring mechanism for raising the plow, a lifting foot lever mounted upon and applied directly to the 15 toggle joint of said connection, a depressing foot lever having a toggle connection with the said lifting foot lever, and means for varying the tension of said spring.

5. In a wheeled plow, the combination of 20 20 a toggle connection for raising the plow, a lifting foot lever mounted upon and applied directly to the toggle joint of said connection, a depressing foot lever having a toggle connection with the said lifting foot lever, 25 a hanger adjustably mounted on the frame, and a spring connecting said hanger and toggle.

6. In a wheeled plow, the combination with a frame, a bail of a lifting spring adjustably connected to said frame and bail, a 30 toggle connection for raising the plow, a lifting foot lever mounted upon and applied directly to the toggle joint of said connection, and a depressing foot lever having a 35 toggle connection with the said lifting foot lever.

7. In a wheeled plow, the combination with a frame, a bail of a hook member clamped to said bail of a lifting spring adjustably connected at one end of said frame 40

and the other end of said hook, a toggle connection for raising the plow, a lifting foot lever mounted upon and applied directly to the toggle joint of said connection, and a depressing foot lever having a toggle connection with the said lifting foot lever. 45

8. In a wheeled plow, the combination with a frame, a bail of a lifting spring adjustably connected to said frame and bail, a toggle connection for raising the plow, a 50 lifting foot lever mounted upon and applied directly to the toggle joint of said connection, a depressing foot lever having a toggle connection with the said lifting foot lever, and means for releasing the tension of said 55 spring when the plow is in the ground.

9. In a wheeled plow, the combination with a frame, a bail of a lifting spring adjustably connected to said frame and bail, a toggle connection for raising the plow, a 60 lifting foot lever mounted upon and applied directly to the toggle joint of said connection, a depressing foot lever having a toggle connection with the said lifting foot lever, and means for releasing the tension of said 65 spring when the plow is in the ground, said means comprising a hook clamped to said bail and adapted to swing rearwardly when the plow is lowered.

10. In a wheeled plow, the combination of 70 a frame, of a bail, of a hooked member clamped to said bail, of a lifting spring connected at one end to said frame and at the other end to said hook.

Signed by me at Rock Island, Illinois, 75 this 13th day of March, 1907.

WILLIAM E. JOHNSON.
